W. M. ROBINSON,
AIR COCK,
APPLICATION FILED JAN. 10, 1918.

1,389,384.

Patented Aug. 30, 1921.

UNITED STATES PATENT OFFICE.

WALTER M. ROBINSON, OF ARLINGTON, MASSACHUSETTS, ASSIGNOR TO VICTORY EQUIPMENT CORPORATION, OF BOSTON, MASSACHUSETTS, A CORPORATION OF MASSACHUSETTS.

AIR-COCK.

1,389,384.

Specification of Letters Patent. Patented Aug. 30, 1921.

Application filed January 10, 1918. Serial No. 211,293.

To all whom it may concern:

Be it known that I, WALTER M. ROBINSON, a citizen of the United States, residing at Arlington, in the county of Middlesex and 5 State of Massachusetts, have invented new and useful Improvements in Air-Cocks, of which the following is a specification.

The object of this invention is to provide an improved valve for use in high pressure 10 pneumatic systems.

On the accompanying drawing, I have illustrated, and I shall hereinafter describe in detail, one embodiment of the invention, which is the best form now known to me, 15 but which is capable of various modifications and changes in the details of its construction and arrangement of parts without departure from the spirit of the invention as outlined in the appended claims.

20 Referring to said drawings,

Figure 1 represents a side elevation of the valve.

Fig. 2 represents a longitudinal vertical section of the valve, the dotted lines indicating variations in the structure at one of the 25 nipples to enable it to be connected or coupled to complementary members of the air conduit.

Fig. 3 represents a horizontal section on 30 the line 3—3 of Fig. 2.

Fig. 4 represents a vertical section through the plug, the lower end of which is broken away.

Fig. 5 represents the main casing in section and illustrates the formation of lubricating ducts in the plug seat.

In accordance with the present invention, 35 my improved valve is provided with a frusto-conical seat, surmounted at its reduced end by a spring chamber, in which there is located a compression spring arranged to exert pressure against a frusto-conical plug to draw it into its seat.

Proceeding to a more detailed description 40 of the particular embodiment of the invention illustrated on the drawings, the valve casing is indicated as a whole at 10, and is shown as having a substantially cylindrical exterior with exterior projecting flush ribs 45 11, 11, on both sides so that it may be grasped by a wrench or other implement. Projecting in opposite directions from the lower portion of the casing are coupling

members by which the valve as a whole may be attached to the conduit members of the 55 system. As shown by Fig. 1, these coupling members may consist of threaded nipples or male members 12, 13, the former being cylindrical and the latter tapering. Either or both of these members may be varied to suit 60 particular requirements. For example, the member 13 may be unthreaded and extended and provided with a circular flange as shown in dotted lines at 14, or it may be formed as a female internally-threaded nipple as indicated in dotted lines at 15. These particular features of construction, being standard, 65 form no part of the present invention.

Extending transversely through the casing, and communicating with the bores of 70 the nipples, is an aperture 16 which communicates with the plug or valve seat 17 and which forms inlet and outlet ports. This seat 17 is ground frusto-conical and it is open at both ends, the larger end being at 75 the bottom. The plug 18 is likewise frusto-conical, and is carefully ground so as accurately to fit the seat. The plug has a transverse port 19 or passageway which may be brought into registration with the ports 80 formed by the aperture 16, and which is of larger size than the diameter of said aperture, so that the capacity of the valve will not be affected by longitudinal adjustment 85 of the plug as the parts become worn or are reground. The plug may be cast hollow as shown to lighten it, its lower end being solid and closing the larger end of the frusto-conical seat 17.

Above the seat, the casing is formed with 90 a bonnet which furnishes a relatively large spring chamber 20 having a shoulder 21 at its lower end upon which is seated a powerful compression spring 22. The plug is formed with a reduced cylindrical stem 23 95 extending upwardly from the smaller upper end through the spring chamber and sufficiently small in diameter to leave ample space between it and the wall of the spring chamber for the spring. A cap 24 is secured 100 to the stem and against it bears the upper end of the spring, thereby firmly to draw the plug endwise into its seat. The cap is located on an angular (hexagonal if desired) portion 25 of the stem and abuts a shoulder 105 26 thereon. A nut 27 on the threaded ex-

tremity 28 of the stem removably clamps the cap against the shoulder 26. Said cap has a depending marginal flange which incloses the upper end of the spring chamber, and affords a fairly tight fit. To prevent the plug from being rotated through an arc of more than 90° in closing, the casing and the cap have coöperative stops 29, 30, respectively.

10 A handle for operating the plug is desirable and it may be secured to the stem of the plug. With convenience it may be cast as an integral part of the cap and project radially therefrom as indicated at 31.

15 It is frequently desirable to lubricate the plug and its seat. Hence I have shown the plug stem as having a bore 32, the upper end of which is closed by a screw plug 33 and the lower end of which has lateral outlets 34, 34, terminating between the planes of the upper and lower ends of the plug seat 17, and I have also shown the seat as having vertical grooves 35 which terminate between the ends thereof, with which said 25 outlets may register when the plug is oscillated. Preferably the grooves are located at points where the outlets will not register therewith when the plug is at the extremes of its oscillatory movement. Any suitable 30 lubricant, grease or oil is introduced into the bore of the plug stem, and the screw plug inserted in place. Any other means for affording lubrication of the parts may be employed.

35 In disassembling the parts, the nut 27 is removed, the cap and handle slipped from the end of the stem, and the plug is moved in the direction of its larger end. The seat and the plug may now be reground. To assist 40 in regrounding the plug, its lower and larger end is cast with a reduced angular boss 36 having a reëntrant centering point 37 so that it may be easily grasped by and centered in the chuck of a grinding spindle without in-

45 jury. An advantage of the construction which I have described is the simplicity of the structure, which renders unnecessary and in fact prevents variation in the spring pressure by 50 attempts to adjust the parts. The spring is placed under the desired degree of compression between the shoulder 21 and the cap, when the nut 27 is forced home sufficiently to seat the cap against the shoulder 26 of 55 the stem, and of course a spring of such strength as may be necessary is initially selected. Other advantages are due to the ease with which the parts may be assembled and taken apart, to the formation of the spring 60 chamber and its closure to prevent access of dust thereto, and to the facility with which the plug and its seat may be ground and reground.

Having thus explained the nature of my 65 said invention and described a way of mak-

ing and using the same, although without attempting to set forth all of the forms in which it may be made, what I claim is:—

1. An air valve comprising a casing provided with laterally projecting coupling members and having a frusto-conical seat and a bonnet which provides a spring chamber above the smaller end of said seat, a plug in said seat having an unobstructed frusto-conical contour and having a shoul- 70 dered stem at its smaller end extending through said spring chamber and having its larger end solid and closing the larger end of said seat, a cap seated against the shoulder on said stem and having an annular flange overlapping the bonnet, a handle extending from said cap, a nut on said stem clamping the cap against said shoulder, and a spring located in said chamber and having one end bearing against the bottom of said 85 chamber and its upper end bearing against said cap and acting to hold said plug in constant close bearing relation to said seat.

2. An air valve comprising a casing having a central frusto-conical chamber or seat 90 with outlet and inlet ports leading thereto, and having a bonnet furnishing a shoul- dered spring chamber axially surmounting the central seat, a plug in said central chamber having an unobstructed frusto-conical 95 contour and having a reduced stem at its smaller end extending axially through said spring chamber, the larger end of the plug being solid and completely closing the larger end of said central chamber, and said plug 100 having a lateral through passageway for registration with said outlet and inlet ports, a combined handle and cap on said stem closing the upper end of said spring chamber, means for securing the handle on the stem, 105 and a spring in said spring chamber, encircling the stem and having one end bearing against an internal shoulder in the spring chamber, and the other end acting to hold 110 said plug continuously into engagement with its seat.

3. An air valve, comprising a casing having a frusto-conical valve seat therein, a valve plug having an unobstructed frusto- 115 conical contour located in said valve seat, a shouldered spring chamber located above the small end of the valve seat, a stem on the small end of the valve plug extending through said spring chamber, a combined cap and handle on the end of said plug hav- 120 ing an annular flange fitting snugly about the upper end of the chamber, a spring in said chamber bearing at its ends against said shoulder and said cap and exerting pressure tending to draw the valve plug upward in 125 uniformly close fitting relation in said seat to compensate for wear.

In testimony whereof I have affixed my signature.

WALTER M. ROBINSON.
